UNITED STATES PATENT OFFICE.

EDMUND TWEEDY, OF DANBURY, CONN., AND GEORGE YULE, OF NEWARK, N. J., ASSIGNEES, BY DIRECT AND MESNE ASSIGNMENTS, TO THE HAT CURLING MACHINE COMPANY, OF DANBURY, CONN.

HAT-MACHINE TOOL-COUPLER.

SPECIFICATION forming part of Letters Patent No. 317,426, dated May 5, 1885.

Application filed September 4, 1884. (No model.)

To all whom it may concern:

Be it known that we, EDMUND TWEEDY and GEORGE YULE, citizens of the United States, respectively residing in Danbury, Connecticut, 5 and Newark, New Jersey, have invented certain new and useful Improvements in Hat-Machine Tool-Couplers, fully described and represented in the following specification and the accompanying drawings, forming a part of the 10 same.

This invention consists, primarily, in the combination, with a rotating hat-clamp, of two vibrating tool-carriers mounted in such manner as to traverse an uneven or elliptic path 15 in reference to the body of the rotating hat, and in a vibrating coupling device for connecting such tool-carriers, so that both will participate in any movement that may be imparted to either.

20 In order that different tools may be successively used in such coupled carriers, it becomes necessary to provide means for adjusting one or both of the carriers or tools in relation to the coupling devices; and this invention therefore includes such means of adjustment, as 25 well as a stop for determining its limit.

It also includes means for compensating the lost motion in the coupling device, means for withdrawing the tools from the hat-plate, both 30 for removing the hat and changing the plate, means for supplying air and gas to the heating-burners, and the combination and arrangement of various details of construction. These 35 improvements will be understood by reference to the annexed drawings, in which—

Figure 1 is a front elevation of a machine illustrating our invention as applied to a pair of the rocking arms described and claimed in another patent application, No. 142,205. Fig. 2 40 is a view of the rear part of the frame, showing merely the coupler and the gas-connections. Fig. 3 is a side view of the entire machine. Fig. 4 is a plan of the same. Fig. 5 is a side view, and Fig. 6 a front view, of the rocking arm detached from the machine, the side view including the nut for the setting-screw, the clamp-nut, the rock-shaft, and one segment, and the front view including the carrier-guide and its adjustable supporter. Fig. 7 is 45 a front view of the vibrator-arm and cam-rol-

ler. Fig. 8 is a plan of the same with the roller removed, and showing the setting-screw; and Figs. 9, 10, and 11 are a side view, plan and end view of certain parts of a machine, with rectilinear vibrators, showing an alternative mode of applying the coupler to two such vibrators.

In Fig. 10 the tool-carriers and their guides are omitted from the view, and Fig. 11 exhibits merely the outer end of one of the carriers, 60 guides, and rectilinear vibrators.

The invention is shown herein as applied to a hat-curling machine provided with two tools mounted at opposite sides of a rotating hat-clamp and hat-plate for supporting the brim 65 of the hat; but as the invention is equally applicable to machines for ironing hats, and for trimming, softening, and paring brims, we have used general terms for the various parts of the construction.

In Figs. 1 to 8, inclusive, A is a pedestal of T section, provided with a flange or foot, A', a bearing, A², at the top for the spindle of the hat-plate, cam, and clamp, front and rear bearings, A³ and A⁴, for the driving-shaft, and side extensions carrying bearings E' for the rocking-shafts. The hat-clamp B is mounted at the top of the pedestal on a spindle, B', in the bearing A². It may be made of any desired construction, but is assumed to be of the expansion brow-block class; and a hand-wheel, B², is shown in Fig. 1 for actuating such block and clamping the hat, either with or without the hat-plate B⁴. Gears B⁷ connect the spindle B' with the driving-shaft C, the front end 75 of which extends through the pedestal, with the remainder fitting into and beyond the horizontal bearings A³ and A⁴, the rear one of which is enlarged to receive a sleeve, e, which is formed with a pulley, C', at its outer end, 80 and a toothed hub, c', at its inner end.

Between the bearings A³ A⁴ is located a toothed clutch, c², which is feathered upon the shaft C, so as to rotate the shaft when the clutch is engaged with the toothed hub c', the 85 pulley C' being driven continuously by a belt. (Not shown.) A clutch-lever, c³, is jointed to the pedestal and to a shifter, C², which projects to the front of the machine, beneath the hat-clamp, so as to be readily reached by the oper- 90 95 100

ator, the clutch being shown uncoupled in the drawings, as in Figs. 3 and 4. With this construction the driving mechanism is confined entirely to the rear of the machine, and the hat-clamp is so located at the top of the pedestal as to be peculiarly accessible to the operator. The tools b shown as curling-irons herein are represented as held by carriers D , which latter are movable to and from the hat-clamp in guides D' . These guides are pivoted to rocking arms or holders G , at b' , in such manner that the carriers swing freely up and down, so that the tool may rest upon the hat by its weight alone, when desired.

15 In the drawings two rocking arms are shown, one hinged at each side of the hat-clamp upon rocking shafts E E' , the latter being journaled in bearings E' E' , projected from opposite sides of the pedestal A , and the vibrating ends of 20 the arms being extended opposite the sides of the hat-clamp, so as to sustain the tools in contact with the hat.

25 The coupling device consists in a pair of toothed segments, F , secured to the rear ends of the rocking shafts upon their adjacent sides, with the teeth on the segments interlocked, so that when either of the arms or holders is 30 oscillated a precisely similar movement is imparted to the other.

30 To press the tools toward the hat-clamp, a weight, W , is shown attached to one of the segments in Figs. 2, 3, and 4 by a hook, W' . With such construction but one connection is required between the holder and the cam or 35 other oscillating device, and such connection is shown as a vibrator-arm, H , pivoted upon the same center as one of the rocking arms G , and provided with a roller, H' , arranged to bear upon the edge of the hat-plate B^4 , which plate has 40 its edge suitably shaped to act as a cam, B^5 , and impart the desired oscillating motion. The vibrator is furnished with a curved slot, a' , to fit a clamping-bolt, a , inserted through the arm G . As the vibrator H has a uniform 45 stroke, while the arm or holder G must hold the tool nearer to or farther from the clamp to suit brims of different widths, means is required for setting the arms in various relations to such vibrator. A setting-screw, a^2 , is 50 therefore fitted to a bearing, a^3 , and nut a^4 upon the arms G and H , respectively, to set the rocking arm in any desired relation to the vibrator, as may be required to set the tool 55 into an operative position at any desired distance from the center of the hat-clamp. This means of adjustment is for a purpose totally different from the movement of the carrier to and from the hat-clamp in its guide, that movement being intended merely to clear the 60 tools from the hat and not being necessarily combined with any means for securing the carrier in various positions intermediate to its extremes of movement. The clamp-bolt a serves to bind the holder or arm G rigidly to 65 the vibrator or arm H , after the former has been adjusted for any specific tool or hat, by turning the setting-screw a^2 .

To guide the operator in thus setting the holder, we commonly use a graduated scale affixed to the arm G or H , but have not shown 70 the same herein, as we have made it the subject of a separate patent application.

To move the tool-carrier in its guide, we have shown the former provided with a rack, b^2 , upon its lower side, adjacent to the pivotal shaft b' , and provide the latter with a toothed pinion, b^5 , and with a head adapted to receive a crank, b^3 , as shown in Fig. 1; or a hand-wheel may be affixed thereto. The rear end of the carrier is provided with an adjustable stop, b^4 , projecting from its bottom at such point as to strike the guide D' when the carrier is properly set.

With the curling-tools shown herein the machine is operated as follows: A hat of 85 known size and width of brim is secured upon the hat-clamp, and both the carriers thrown forward by turning the pinions b^5 and moving the carriers until arrested by the stops b^4 . The clamp a is then loosened, and the setting- 90 screw a^2 is turned until either of the tools is correctly set to operate upon the hat-brim. The other tool is then adjusted to operate simultaneously by altering its stop b^4 and moving the carrier into the required position. When 95 correctly adjusted, the hat may be curled, and the tools then be quickly retracted to remove the hat by turning the pinions b^5 . The provision of the stop will then obviously afford the means of restoring the tools to the same operative 100 position for any number of similar hats, provided the tools are unchanged; and should it be necessary to change a tool upon one or both sides of the hat, the stop then affords the means to adjust such tool correctly and to re 105 set it repeatedly in the same position.

By the coupling of the tools together the vibrating mechanism is not only simplified, but it is also obvious that the motion of one tool will correspond more accurately with that of 110 the other than if moved by separately vibrating agencies. This is of especial importance in the curling of hats, particularly when the curl is formed by tools acting independently of the hat-brim plate, as the curl is then supported only by the tools and is distorted when 115 the two tools do not follow the same curve. The coupling of the tools together also secures a great advantage in advancing the tools simultaneously while the machine is in motion, as 120 certain operations like curling may be much more easily and perfectly performed if the action of the tools upon the brim is gradual. Such application of the tools may be made with our construction by loosening the clamp 125 a sufficiently to permit the action of the setting-screw, and then setting the tools into their primary operative position. The curling may then be commenced without tightening the clamp, and the tools may be simultaneously 130 and gradually advanced during the progress of the work until the tools reach their final operative position and the curling is completed.

In Fig. 1 the tool at the right-hand side is

shown in its operative position, and a breaker, *f*, hinged to the top of the guide *D'*, is shown in suitable position to co-operate with the curling-iron *b*. At the left side, however, the stop 5 at the rear of the carrier is shown retracted, and the breaker turned up above the guide to remove the hat. The stop *b*⁴ is thus exposed more clearly to view, and consists, as is also seen in Figs. 3 and 4, of a flat piece notched 10 into the rear end of the carrier, and held thereto by an adjusting-screw, which has a round milled head, *s*. The lower end of the stop projects below the carrier, and thus strikes the body of the guide *D'* when the carrier is thrown 15 forward. The sliding carriers, being intended merely to retract the tools when replacing the hats, need not be constructed to draw entirely away from the top of the hat plate *B*⁴; and to secure any further withdrawal of the tools, so 20 as to remove the hat-plate, it is desirable to move the vibrator itself from contact with the plate and hold it back, with the affixed rocking-arm, by a suitable catch attached to the pedestal *A*. Such catch is shown in Figs. 1, 25 3, and 4, as a sliding spring-bolt, *e*, inserted in a boss, *e'*, upon the top of the bearing *E'*, behind the vibrator-arm *H*, and the latter is formed with a hole, *e*², corresponding with the bolt when the vibrator is drawn back, as described. 30 When thus drawn back, the bolt is automatically shot into the hole *e*² by a spring, *e*³, inclosed in the boss *e'*. The coupler thus operates, when the single vibrator-arm is drawn back, to hold both the rocking-arms backward 35 at once, and to withdraw the tools entirely away from over the hat-plate. The hat-plate may then be readily removed from the clamp, if made detachable, and others of different shape at the edge be substituted, so as to actuate 40 the tools in any desired curve. A knob, *e*⁴, is shown fixed to the end of the bolt, by which it is pulled back from the hole *e*², when the machine is again ready for use. The spring-catch may be applied to the vibrator in other 45 ways, as its essential feature is its automatic action when the vibrator is pulled back into an inoperative position.

The term "vibrator" applied above to the arm *H* may obviously be construed to cover 50 any means by which the required vibratory movement is given to the tool carriers or holders, and as it is common to actuate the vibrator in various ways in other machines, the arm *H* or either of the arms *G* may be vibrated by 55 any other suitable means that may be preferred.

To illustrate a modification of the vibrator and coupler, we have shown in Figs. 9, 10, and 11 a machine constructed with rectilineal 60 vibrators, to which a segmental coupler could not so readily be attached. In these figures the tool-carriers and pivoted guides are the same as in the other figures; but the holders *G* are shown as dovetailed slides fitted to 65 fixed ways *G'* upon a bed, *A*⁵, at opposite sides of the clamp, and a separate cam, *B*⁷, is affixed to the spindle *B'* beneath the plate *B*⁴. The

vibrator consists of a bar, *H*, fitted to one of the holders *G* by a screw, *a*², and carrying a roller, *H'*, in contact with the separate cam *B*⁷. 70 The holders are coupled together by means of links *F'* and by a central lever, *F*, pivoted upon the spindle *B'*, the inner ends of the links being attached to the opposite ends of the lever, so as to move in the equal and similar manner required for tools applied at opposite sides of the same hat. The weight *W* is in this construction attached to a cord carried over a pulley, *w*, and secured to the holder *G* opposite the vibrator *H*. The weight thus serves 80 not only to press the tools toward the hat-clamp and the vibrator toward the cam, but, as it acts in opposition to the latter, it operates to neutralize all the lost motion in the joints of the links *F'*, and thus secures the most 85 exact coincidence in the movements of the coupled tools. The same effects are secured in the machine with coupled rocking arms by attaching the weight to the segment *F* most remote from the vibrator, as shown in Fig. 2. 90 If preferred, the weight *W* may be replaced by a spring, without, however, securing such uniform pressure.

In practice we make the weight in sections, and apply only enough to force the tools against 95 the felt and bend or operate upon it in the desired manner. The roller *H'* provided upon the vibrator is quite immaterial, as its function is merely to reduce the friction, and a bearing-shoe is used in other machines for a similar purpose.

From the above illustrations it will be seen that the coupler, the vibrator, the tool-carrier, and other mechanical elements of our invention may be materially altered in form to perform the same function in different machines; and we do not therefore limit ourselves to the constructions shown herein for carrying out our invention.

In the machine shown in Figs. 9, 10, and 11 the setting-screw *a*² is used effectively without any clamp-bolt *a*, and the latter is not essential to the operation of the arms *G* and *H* when united by the screw *a*², as shown in the other figures.

The term "hat clamp" is used herein as an equivalent for any means whatever that may be adapted to rotate the hat in proximity to the tools, and is not therefore specifically described or claimed.

In Figs. 1, 3, and 4 are shown two treadles, *I*, pivoted separately to the standard *A* near its base, at *h*, and connected separately to the jointed tool-carriers *D* by means of connecting-rods *l*; the rods being preferably fitted 125 to the treadles by ball-and-socket joints *m* to compensate for the various movements of the treadles and carriers, as the latter are applied to and removed from the hat.

By pressure upon the treadle at the latter 130 stage of the curling operation the workman may compress the curl with any degree of force, and thus greatly aid the iron, especially in forming such curls as the Anglsea,

which are pressed down flat upon the hat-brim, to thoroughly break the bend or fold of the felt. A ball, I' , (shown in dotted lines,) upon an extension, I^2 , of the treadle lever, behind the fulcrum, may be used, if desired, to balance a part of the weight of the tool or carrier.

By the use of independent treadles the opposed tools may be actuated separately, and are thus better adapted for performing different operations simultaneously upon the same hat, as required in many processes.

In Figs. 1 and 12 is shown a gas jet of special construction, adapted to project a flame into the heated tools from some external point.

15 The construction consists in a nozzle, f , screwed into a socket, g , each of these parts being formed with a separate pipe-connection, d' , and one of them being provided with a shank, g' , for attaching the jet to the tool holder or carrier adjacent to the flame-opening in the iron. The shank may be formed at any angle with the pipe-connection as may best suit the location of the flexible tubes, g^2 . (Shown in Figs. 1, 2, and 3.) The employment of the 20 shank is shown in Fig. 1, where the jet is shown secured thereby to the carrier D in the rear of the curling-iron b , and the flexible pipes are indicated as projecting at the rear of the jet. The socket consists in a chamber 25 into which the gas-pipe connection opens, and is formed with a contracted outlet, g^3 , in which the nozzle is centered. It is also formed with a threaded opening, i , opposite the outlet, for the attachment of the nozzle, the point of 30 which is set even with the mouth of the outlet g^3 . The central bore of the nozzle is penetrated by the air-connection, so that an airblast may be forcibly projected from the nozzle into the midst of the gas which issues from 35 the annular space in the socket about the nozzle. We find that this construction of jet produces a smokeless flame like a blow-pipe, and that the iron is thus much better heated than when the burner is inserted within it.

40 45 We are aware that a gas and air jet is old, and therefore claim only the particular construction herein described.

We are aware that it is common to change the form of a brow-block or of a mold for 50 curling and shaping hat-brims by mechanism which operates to expand or contract the opposite parts equally and simultaneously, and that similar mechanism has been used to press opposed dies or tools toward a mold. We 55 do not therefore claim, broadly, the means for connecting or moving two opposed tools; but, having fully shown the nature of our invention herein, it will be observed that it differs from any previous construction in providing a vibrating coupler adapted to operate 60 vibrating tools and tool-carriers, and that it thus affords the means to dispense with one of the cam rollers or vibrators heretofore used in machines having two tool-carriers vibrated 65 at opposite sides of the same hat. It is therefore restricted to a vibrating coupler applied to vibrating tool-carriers, the vibrating mo-

tion of the latter being intended to traverse the tools in an elliptical or irregular path about a rotating hat, and the invention being 70 therefore claimed in combination with a rotating hat-clamp. The rocking arms are also claimed herein as vibrating rocking arms.

We are aware that machines have been heretofore patented in which a rotating hat-clamp is combined with various forms of tool carriers, holders, and vibrators, and do not therefore claim such parts, broadly, as our invention, but only the novel combinations or constructions herein described.

80 We have restricted our claims herein to the stop b^4 and catch e , exclusively, in combination with a pair of holders or carriers coupled together, as we have claimed the same otherwise in another patent application, No. 142,205, of E. Tweedy and Geo. Yule, and Nos. 142,202 and 142,204, of Geo. Yule.

We have also claimed in other pending applications many constructive features shown but not claimed herein, and we therefore disclaim herein any subject-matter allowed in said patent application. Although we have shown herein a tool-carrier pivoted to a rocking arm in such manner that the tool may rest freely upon the hat-brim, we disclaim a yielding or weighted tool or carrier generically, and we hereby reserve the right on behalf of George Yule to file a separate patent application jointly with Frederick Cocker before the issue of our present claims, for the combination, with a brim-supporting plate, of a curling-tool resting freely upon such plate, and operated by a vibrating holder and tool-carrier.

It is obvious that certain parts of our invention may be used without the others, and, as we have fully described their separate functions above, we claim the same in the following manner:

1. The combination, with a rotating hat-clamp, of two vibrating tool-carriers, a coupler, substantially as described, adapted to vibrate with the said carriers, and a vibrator having a connection with one of said carriers and operating to vibrate them both to and from the hat-clamp.

2. The combination, with a rotating hat-clamp, of two vibrating tool-carriers mounted upon opposite sides of such clamp, means for vibrating one of the carriers to and from the hat-clamp automatically, and a vibrating coupler, operating as described, for uniting such carrier to the opposite one and imparting a coincident and similar vibrating movement thereto.

3. The combination, with a rotating hat-clamp, of two tool-carriers mounted upon vibrating rocking arms, coupled together by means substantially as described, and mechanism for vibrating one of the arms and tool-carriers to and from the hat-clamp.

4. The combination, with a rotating hat-clamp, of two vibrating tool-carriers mounted upon vibrating rocking arms, the arms being

- rigidly attached to rocking shafts E, and the shafts E being connected by a coupler, substantially as described, and means applied to one of the arms for vibrating the carriers automatically to and from the hat-clamp.
5. The combination, with a rotating hat-clamp, of two vibrating tool-carriers coupled together, substantially as described, means applied to one of the carriers to press the tools toward the hat-clamp, and means for vibrating one of the carriers to and from the hat-clamp.
6. The combination, with a rotating hat-clamp, of two tool-carriers mounted upon vibrating rocking arms, a coupler consisting of toothed segments connected with the arms, means for vibrating one of the arms and segments, and a weight or spring attached to the other segment to press the tools toward the clamp.
15. The combination, with a rotating hat-clamp and two vibrating tool-holders coupled together by a vibrating coupler, as described, of tool-carriers movably attached to the holders, means for moving the carriers upon the holders to and from the hat-clamp for removing and replacing the hat, and adjustable stops for setting the carriers upon the holders in the desired relation to one another when applied to the hat.
25. The combination, with a rotating hat-clamp, of two vibrating tool-carriers mounted upon opposite sides of such clamp, and coupled together by a vibrating coupler, as described, means for pressing the carriers toward the hat-clamp, as by a spring or weight, and a catch operating upon one of the carriers when withdrawn from the hat-clamp to lock both the carriers in an inoperative position.
35. 9. The combination, with a hat-clamp and cam rotated upon the same axis, of vibrating rocking arms pivoted upon opposite sides of such clamp and cam, and coupled together by a vibrating coupler, as described, a shoe upon one arm to bear upon the cam, means—as a weight or spring—for pressing the arm with the shoe toward the cam, and a catch operating automatically upon one of the arms when withdrawn from the hat-clamp or cam to lock both the carriers in an inoperative position.
45. 10. The combination, with the rotating hat-clamp and brim-table, of the vibrating rocking arm pivoted by one end, a tool-carrier mov-
- able to and from the hat-clamp in a guide pivoted upon the free end of the arm, and a treadle connected with the carrier for producing a temporary pressure.
11. The combination, with the tool-carrier, pivoted so as to rise and fall when in operation, and to be moved from the hat-clamp for removing the hat, of the treadle and the connection united thereto by a ball-and-socket joint.
12. The combination, with the pedestal A, of the bearing A² at the top, the hat-clamp and its spindle supported thereby, the bearings E' E' at the opposite sides, the rocking arms and tool-carriers supported thereby, and means for rotating the hat-clamp and vibrating the arms.
13. The combination and arrangement of the pedestal A, bearing A² at its top, supporting the hat-clamp, spindle, and cam, the bearings E' E' supporting the rocking arms and tool-carriers, the bevel gears B⁶ and B⁷, the driving-shaft and clutch supported behind the pedestal, and the shifter C², extended to the front of the machine.
14. The combination and arrangement of the pedestal having the hat-clamp supported at the top, the two rocking arms pivoted at opposite sides of the clamp and in front of the pedestal, the rock-shafts extending to the rear of the pedestal, and coupled by the toothed segments, and the variable weight attached to one of the segments.
15. The combination, with a rotating hat-clamp and cam rotating therewith, of a rocking arm provided with a tool-carrier, and a vibrator-arm pivoted upon the same fulcrum as the rocking arm, and means for adjusting one arm to the other.
16. The means for holding and adjusting the cam-roller or shoe upon the rocking arm, consisting in the vibrator-arm pivoted upon the axis of the rocking arm, the setting-screw connected with both arms, and the clamping-bolt for binding the two arms together when adjusted.
- In testimony whereof we have hereunto set our hand in the presence of two subscribing witnesses.
